DESIGN FOR A PLATE COVER

Lurelle Guild, Noroton, Conn., assignor to Kensington, Incorporated, New Kensington, Pa., a corporation of Pennsylvania

Application November 6, 1934, Serial No. 53,902

Term of patent 3½ years

To all whom it may concern:

Be it known that I, Lurelle Guild, a citizen of the United States, residing at Noroton, in the county of Fairfield and State of Connecticut, have invented a new, original, and ornamental Design for a Plate Cover, of which the following is a specification, reference being had to the accompanying drawing, forming a part thereof.

Fig. 1 is a top view and Fig. 2 is a side view of a plate cover embodying my new design.

I claim:

The ornamental design for a plate cover, as shown.

LURELLE GUILD.
